UNITED STATES PATENT OFFICE.

HENRY H. STRATTON, OF JOHNSON CITY, TENNESSEE.

SEWING-MACHINE ATTACHMENT.

SPECIFICATION forming part of Letters Patent No. 565,705, dated August 11, 1896.

Application filed May 23, 1895. Serial No. 550,442. (No model.)

To all whom it may concern:

Be it known that I, HENRY H. STRATTON, a citizen of the United States, residing at Johnson City, in the county of Washington and 5 State of Tennessee, have invented a new and useful Sewing-Machine Attachment, of which the following is a specification.

This invention relates to an improvement in quilting-frame attachments for sewing-machines, and the object in view is to provide a quilting-frame in which the rollers are held in place by novel means, the precise nature of which will be hereinafter disclosed, such means adapting the rollers to be readily removed and replaced whenever found necessary.

The invention consists in certain novel features and details of construction and arrangement of parts, as hereinafter fully described, 20 illustrated in the drawings, and finally pointed out in the claim hereto appended.

In the accompanying drawings, Figure 1 is a perspective view of the improved quilting-frame and its supporting-carriage complete 25 and constructed in accordance with this invention. Fig. 2 is an inside elevation of one end of one of the frame-bars of the quilting-frame, showing the retaining-pawl and also showing, in dotted lines, the lower position 30 of one of the end rollers. Fig. 3 is a sectional view showing the relative arrangement of one of the rollers and its retaining-pawl with the end bar of the frame. Fig. 4 is also a sectional view of the same parts, showing 35 the manner in which the spindles of the rollers are let into the side bars of the frame and showing also the form of the retaining-pawl in cross-section. Fig. 5 is a bottom plan view of one of the retaining-paws. Fig. 6 is a de- 40 tail view of the spindle, ratchet-wheel, spacing-hub, and the square shank, which are formed into one piece and applied to the ends of each roller. Fig. 7 is a broken view looking toward the inner face of one of the side 45 bars, showing the form of the slotted plate by means of which the central longitudinal frame and spacing-bar is secured at its ends to the frame end bars. Fig. 8 is a longitudinal section through one of the end bars and the 50 adjacent end of the longitudinal spacing-bar, showing the manner of connecting the same. Fig. 9 is a longitudinal section through the

carriage or hanger, showing the manner of securing the ends of the upper sections of the inclined supporting-rod. Fig. 10 is a 55 transverse vertical section through the same.

Similar numerals of reference designate corresponding parts in the several figures of the drawings.

Referring to the drawings, the end bars of 60 the frame (indicated at 1) are preferably made of hard wood, may be of any desired length, and are enlarged at either end and centrally to accommodate the several winding-rollers and the longitudinal spacing-bar hereinafter 65 described. The end bars 1 are provided with retaining-plates 2 upon their inner adjacent faces, said plates being provided each with a pair of keyhole-slots 3 and arranged within recesses or depressions in the inner faces 70 of the end bars so as to be flush therewith, as indicated in Fig. 7, although, if preferred, said retaining-plates may be simply secured to the inner faces of the end bars without being let into recesses or depressions, as 75 shown in Fig. 8.

The slots 3 are adapted to permit the heads of screws secured to the ends of the spacing-bar to pass through them, after which the screw-heads may be moved lengthwise of said 80 end bars, so as to engage the shanks of the screws with the narrow portions of the key-hole-slots, in which position the screw-heads will engage against the outer opposite faces of the retaining-plates. 85

The end bars 1 have perforations 5 extending through them in line with the screw-heads 4 for permitting the point of a screw-driver to be passed through said perforations for the purpose of tightening the screws and afford- 90 ing a firm and rigid connection between the end bars of the quilting-frame and the longitudinal spacing-bar thereof, (indicated at 6.)

Three rollers 7, 8, and 9 are arranged with- 95 in the frame above described, extending longitudinally from one end bar to the other and journaled therein. These rollers are pref- 100 erably made of wood and are each provided at either end with spindles 10 and ratchet-wheels 11. The spindle 10 and the adjacent ratchet-wheel are formed in one piece, and, as will be seen by reference to Fig. 6, the ratchet-wheel is provided upon its inner face with an integrally-formed spacing-hub 12, be-

yond which is an inwardly-extending square shank 13, all of said parts being preferably cast or otherwise formed in a single piece. The square shank 13 is inserted in a corresponding socket in the end of its respective roller until the spacing-hub 12 abuts snugly against the adjacent end of the roller, and the spindle 10 is adapted to be inserted in a cylindrical socket 14, a series of which is provided in the inner adjacent faces of the end bars 1.

15 designates a pawl which is mounted upon the inner end of a threaded bolt 16, extending through the end bar 1, said pawl being secured in place by means of a thumb-nut 17, by means of which the pawl is adapted to be tightened or loosened for holding the same in engagement with the ratchet-wheel 11 or for throwing the same out of engagement therewith when desired. The free end of the pawl 15 is considerably increased in width and is recessed upon its under side, as indicated at 18, a series of teeth 19 being formed within said recess for the purpose of 20 engaging the ratchet-wheel 11. By means of this construction an oppositely-disposed pair of downwardly-projecting spacing-flanges 20 and 21 are formed, being adapted to lie upon either side of the ratchet-wheel, this arrangement 25 serving to regulate the distance between the end bars and the adjacent ends of the rollers and to preserve the same in their proper working relation. The rollers being shorter than the space between the end bars 1, when the swinging end of the pawl 15 is introduced between the end bar to which it is pivoted and the adjacent end of its respective roller the latter is not only prevented from rotating, but longitudinal movement of 30 the roller is also prevented. By rocking the pawl out of engagement with the roller the latter may be moved longitudinally and its spindles thereby disengaged from the bearing-sockets in the end bars, thus allowing the 35 said roller to be entirely removed from the quilting-frame.

By reference to Fig. 2 it will be seen that the positions of the outside rollers 7 and 9 may be changed as to their height. To accomplish this, either end of each end bar is provided with upper and lower cylindrical sockets 14, adapted to receive the spindles of said rollers, said sockets being equally distant from the pivotal bolt 16, upon which the 40 pawl 15 is mounted, so that said pawl may engage the ratchet-wheel 11 when the roller is adjusted to either position. This provision is made in order that the material from which the quilt is to be made may be drawn 45 tightly beneath the central longitudinal spacing-bar 6, above referred to.

Each of the rollers has a piece of fabric tacked or otherwise secured around the same. The material of which the top of the quilt is 50 to be formed, and indicated at 22, is stitched at one edge to the roller 8 and wound there-

on. The lining (indicated at 23) is stitched at one end to the fabric surrounding the roller 9. The top material passes beneath the longitudinal spacing-bar 6 and the lining 55 passes beneath the top 22, the forward edges of the top and lining being both stitched to the fabric surrounding the roller 7. The cotton is introduced between the top and the lining by placing it upon the lining between the rollers 8 and 9, and as the front roller 7 is revolved said cotton is fed in between the top and the lining in a manner that will be readily understood.

The traveling carriage or hanger, by means 60 of which the quilting-frame is supported, comprises an oppositely-disposed pair of side plates or bars 24, connected at their upper ends by means of a strip 25 and spaced a sufficient distance apart to receive between them 65 a pair of grooved pulleys 26, mounted upon transverse shafts arranged at either end of the carriage or hanger. The side bars or pieces of the carriage are provided with grooves, oppositely arranged upon the inner 70 faces thereof, and at or near their bottom edges, as shown in Fig. 10, and within said grooves is mounted a removable base-strip 90 75 27, extending longitudinally the full length of the carriage.

28 indicates a block extending longitudinally of the carriage and located beneath the same, said block being provided with inclined perforations at either end for the reception of the upper headed ends of inclined supporting-rods 29, said block being also provided with an upwardly-extending rib 30, entering a corresponding socket in the lower face of the base-strip 27, by means of which the block 28 is held in proper position with relation 80 to the carriage, said block being secured by means of a bolt 31, passing vertically through aligned perforations in the base 27 and block 28 and having a thumb-nut 32, by means of which the block may be clamped firmly 85 against the lower edges of the side bars 24 of the carriage. The object of this construction is to provide means whereby the carriage may be placed upon and removed from the usual overhead wire 33. This may be 90 done by loosening the thumb-nut 32, when the base-strip 27 may be withdrawn longitudinally from the grooves in the inner walls of the side bars 24. After the grooved pulleys 26 have been engaged with and placed 95 upon the wire 33, the base-strip 27 may again be inserted and clamped in place by means of the thumb-nut 32.

The inclined rods or supports 29 are each made in two sections, the lower sections being 100 connected with the quilting-frame, and preferably with the longitudinal spacing-bar 6 thereof. The adjacent ends of the rod-sections are screw-threaded to receive turnbuckles 34, by means of which the length of 105 the inclined supporting-rods 29 may be increased or diminished for adjusting the height 110

of the quilting-frame with a view to rendering the same capable of being used in connection with sewing-machines of different kinds.

5 In operation it will of course be understood that by means of the supporting-wire and carriage the quilting-frame is adapted to be moved bodily across the sewing-machine table and in the path of the needle, during which movement a line of stitches is formed across the material of which the quilt is to be composed, said stitches extending longitudinally of the quilting-frame. Having completed one line of stitches, the pawls are manipulated 10 in such manner as to enable the winding-roller 7 to be partially revolved for bringing another portion of the material of the quilt into line with the path in which the needle travels, all of which is well understood in the 15 art to which this invention belongs.

It will be apparent that various changes in the form, proportion, and minor details of construction may be resorted to without departing from the spirit or sacrificing any of 20 the advantages of this invention.

Having thus described the invention, what is claimed as new, and desired to be secured by Letters Patent, is—

In a quilting-frame attachment for sewing-machines, the combination with a longitudinal spacing-bar, of end bars secured thereto and provided with bearing-sockets, rollers arranged between said end bars and of a length less than the space between the same and having their spindles journaled in said sockets, 30 a ratchet-disk at one end of each roller, and a pawl for said ratchet-disk pivoted to one of the end bars, the swinging end of said pawl being adapted to rest between the said end bar and the adjacent end of the roller, whereby 35 the latter is held against rotation and also against longitudinal movement and displacement, substantially as described.

In testimony that I claim the foregoing as my own I have hereto affixed my signature in 40 the presence of two witnesses.

HENRY H. STRATTON.
